UNITED STATES PATENT OFFICE.

RUDOLPH RUZICKA, OF DOBBS FERRY, NEW YORK, ASSIGNOR TO NEW SAFETY PAPER CO., OF BOSTON, MASSACHUSETTS, A VOLUNTARY ASSOCIATION OF MASSACHUSETTS.

DESIGN FOR SAFETY PAPER.

Application filed August 28, 1922. Serial No. 3,582. Term of patent 3½ years.

To all whom it may concern:

Be it known that I, RUDOLPH RUZICKA, a citizen of the United States, residing at Dobbs Ferry, in the county of Westchester and State of New York, have invented a new, original, and ornamental Design for Safety Papers, of which the following is a specification, reference being had to the accompanying drawing, forming a part thereof.

The figure is a face view, magnified four diameters, of a sheet of paper bearing my new design.

I claim:

The ornamental design for safety paper, as shown.

RUDOLPH RUZICKA.
